DESIGN FOR A COLLAPSIBLE MUSIC STAND

Willie Berg, Chicago, Ill.

Application May 22, 1945, Serial No. 119,671

Term of patent 14 years

(Cl. D33—10)

To all whom it may concern:

Be it known that I, Willie Berg, a citizen of the United States, residing in the city of Chicago, county of Cook, State of Illinois, have invented a new, original, and ornamental Design for Collapsible Music Stand, of which the following is a specification, reference being had to the accompanying drawing, forming a part thereof, in which:

Fig. 1 is a front perspective view of a collapsible music stand showing my new design;

Fig. 2 is a side elevational view thereof; and Fig. 3 is a rear elevational view thereof.

The present design is characterized by the gradually rounded front portion of the pedestal, shown by means of full lines in the drawing.

I claim:

The ornamental design for a collapsible music stand, as shown and described.

WILLIE BERG.
